SAFETY MEANS FOR BATHTUBS

Vincent R. O'Brien, St. Paul, Minn.

Application December 8, 1943, Serial No. 512,802

2 Claims. (CL 4—185)

1

My invention relate to safety means for bathtub and shower bath, wherein it is desirable to provide a safety means to prevent a person's slipping on the floor of the tub or the shower stall.

A feature resides in providing a handle which may be mounted upon the faucet so that it may swing back on to the neck of the faucet where the handle is out of the way when it is not desired for use. In using the bathtub it is sometimes difficult for the person therein to raise himself out of the tub. By providing my safety means, which includes the handle associated with the water faucet, together with a mat or means held on the floor of the tub or of the shower stall such as a sponge rubber mat or other similar non-skid means which is adapted to be held in a fixed relation to the drain outlet of the stall or tub, the bather is protected against slipping or falling when trying to get out of the bathtub.

Further, the invention includes a socket means associated with the drain outlet which is adapted to engage the end of the rod, which rod is anchored in the body of the anti-skid mat which normally lies upon the floor of the tub when it is in use.

In the drawings forming a part of the specification:

Figure 1 is a side sectional elevation of the bath tub showing my safety means in operative position associated therewith.

Figure 2 illustrates a form of faucet and foldable handle used in my safety means as illustrated in Figure 1.

Figure 3 is a plan view of the faucet illustrated in Figures 1 and 2 showing the handle folded back on to the faucet neck.

The drawings illustrate the bathtub A of any ordinary construction which is provided with a drain B for the soiled water and a water inlet faucet C.

The water inlet C may be in the form illustrated in the Figures 1, 2 and 3. In this form of the faucet C, a handle 10 is pivoted at 11 to the forward end of the neck 12 of the faucet C. The handle 10 is shaped to fit over the neck 12 of the faucet C as illustrated in full lines on Figures 1 and 2.

When the handle 10 is desired for use, it is lifted in the direction of the arrow shown in Figure 2 to a pre-determined point, whereupon the bifurcated end which is pivoted at 11 will bear against the shoulders 13 on either side of the neck of the faucet so as to limit the outer movement of the handle 10. These shoulders 13 are illustrated in Figures 2 and 3.

The faucet C may be formed with a hook 14 on

2

the outer end of the same so that if it is desired, a foot rest or mat 15 may be hung when it is not in use.

Thus, with my invention I provide a handle supporting means to assist a bather in getting into or out of a bathtub which supplies a long felt need as many accidents occur as a result of slipping while using a bathtub. The handle 10 is so formed that it is out of the way when not in use and inconspicuous because of its conformity with the shape of the faucet. While I have shown my handle means in a definite form I do not wish to be confined to that specified form but within the scope of the following claims.

15 I claim:

1. A safety means for bathtub in combination with the neck of the water faucet, including a handle pivotally attached to the sides of the neck of the faucet, the body of said handle being formed concaved to fit over the neck of the faucet, and shoulder means for holding said handle in an upright outwardly projecting position for easy engagement by the bather to lift himself out of the tub, said handle fitting over and in close proximity to the neck of the faucet when not in use.

2. A safety means for bathtub in combination with the neck of the water faucet including a handle pivotally attached to the sides of the neck of the faucet, the body of said handle being formed concave to fit over the neck of the faucet, the handle being movable into engaging position whereby a bather may engage said handle for assistance in getting into or out of a bathtub.

VINCENT R. O'BRIEN.
